US00D822952S

(12) **United States Design Patent** (10) **Patent No.:** **US D822,952 S**
(45) **Date of Patent:** **** Jul. 17, 2018**

(54) **GARMENT WITH INTEGRATED HYDRATION SYSTEM**

(71) Applicant: **DGM Creations LLC**, West Palm Beach, FL (US)

(72) Inventors: **Kyle Sola**, Brooklyn, NY (US); **Marcel Geser**, Zurich (CH); **Franziska Rieder**, Zurich (CH)

(73) Assignee: **DGM Creations LLC**, West Palm Beach, FL (US)

(**) Term: **15 Years**

(21) Appl. No.: **29/575,804**

(22) Filed: **Aug. 29, 2016**

(51) LOC (11) Cl. **02-02**

(52) U.S. Cl.

USPC **D2/858; D3/202**

(58) **Field of Classification Search**

USPC D2/840, 731, 858; D3/202

CPC A45F 3/04; A45F 3/20

See application file for complete search history.

(57) **CLAIM**

The ornamental design for garment with integrated hydration system, as shown and described.

DESCRIPTION

FIG. 1 is a front perspective view of an embodiment of a garment with integrated hydration system, according to the claimed design.

FIG. 2 is a front view of the garment with integrated hydration system shown in FIG. 1.

FIG. 3 is a rear view of the garment with integrated hydration system shown in FIG. 1.

FIG. 4 is a right side view of the garment with integrated hydration system shown in FIG. 1.

FIG. 5 is a top view of the garment with integrated hydration system shown in FIG. 1.

FIG. 6 is a front perspective view of a second embodiment of a garment with integrated hydration system, according to the claimed design.

FIG. 7 is a front view of the garment with integrated hydration system shown in FIG. 6.

FIG. 8 is a rear view of the garment with integrated hydration system shown in FIG. 6.

FIG. 9 is a right side view of the garment with integrated hydration system shown in FIG. 6; and,

FIG. 10 is a top view of the garment with integrated hydration system shown in FIG. 6.

The features shown in broken lines are environment only, and not part of the claimed design. The left and bottom views of the garment with integrated hydration system are not shown, and form no part of the claimed design.

1 Claim, 10 Drawing Sheets
